UNITED STATES PATENT OFFICE.

WALTER G. DOTY, OF DAYTON, OHIO.

DESIGN FOR A SUCTION-CLEANER FRAME.

47,257.

Specification for Design.

Patented Apr. 27, 1915.

Application filed June 4, 1914. Serial No. 843,109. Term of patent 3½ years.

To all whom it may concern:

Be it known that I, WALTER G. DOTY, a citizen of the United States, residing at Dayton, in the county of Montgomery, State of Ohio, have invented a new, original, and ornamental Design for Suction-Cleaner Frames, of which the following is a specification, reference being had to the accompanying drawing, forming part thereof.

The drawing is a side elevation of a suction cleaner frame showing my new design.

I claim:

The ornamental design for a suction cleaner frame, as shown.

WALTER G. DOTY.

Witnesses:

C. A. CRAIGHEAD,
CARRIE M. RECKER.
